DESIGN FOR A BOTTLE

Calman Levine, New York, N. Y., assignor to
Joseph E. Seagram & Sons, Inc., Lawrenceburg,
Ind.

Application October 17, 1934, Serial No. 53,662

Term of patent 14 years

To whom it may concern:

Be it known that I, Calman Levine, a citizen of the Dominion of Canada, residing at Montclair Hotel, New York, county of New York, and State of New York, have invented a new, original, and ornamental Design for a Bottle, of which the following is a specification, reference being had to the accompanying drawing, forming a part thereof.

I claim:

The ornamental design for a bottle as shown.

CALMAN LEVINE.
